UNITED STATES PATENT OFFICE

CHARLES H. KEYSER, OF CHICAGO, ILLINOIS.

SIGN-BOARD.

SPECIFICATION forming part of Letters Patent No. 664,871, dated January 1, 1901.

Application filed May 11, 1900. Serial No. 16,259. (No model.)

To all whom it may concern:

Be it known that I, CHARLES H. KEYSER, a citizen of the United States, residing at Chicago, in the county of Cook and State of Illinois, have invented a new and useful Improvement in Sign-Boards, of which the following is a full, clear, and exact description, reference being had to the accompanying drawings, and the letters of reference marked thereon, which form a part of this specification.

This invention relates to an improvement in signs of that class adapted to be held normally in a vertical position by means of a weight attached to the lower end thereof and which are so balanced that they may rock back and forward with the wind while remaining substantially stationary with respect to their support.

The invention consists in the matters hereinafter described, and more fully defined and pointed out in the appended claims.

In the drawings, Figure 1 is a front elevation of a device embodying my invention. Fig. 2 is a section taken on line 2 2 of Fig. 1. Fig. 3 is a section taken on line 3 3 of Fig. 1. Fig. 4 is a fragmentary front elevation of one form of my device.

As shown in said drawings, A indicates a weight of cast metal, herein shown as having the form of one of the halves of a sphere or ball divided in a plane passing through the center and provided with a rod a, extending therethrough parallel with said plane surface and provided on one end with a head in a familiar manner and having at the other end a screw-thread adapted to receive a complementary nut a'. A groove a² is provided parallel with said rod and extending diametrically across the plane surface of said half-ball and adapted to receive a part of the lower ends of the sign-boards B B', herein shown as consisting of two or more boards of any desired material, preferably uniting at their meeting edges with tongue-and-grooved joints. Said boards if of wood are bored transversely to receive the ends of the rod a and are securely clamped thereon by means of a nut a', which, as shown, is set in sufficiently deep in the edge of said sign-board, as is also the head thereto, to present a flush finish. The upper ends of said boards are secured together

by any desired means. As herein shown, a rod b² is provided, which passes transversely through the tops of said boards and is provided on one end with a head and on the other with screw-threads adapted to receive a complementary nut b³ in a familiar manner. Said bolt is of such length that when the same is secured in place, as shown, the head and nut thereof are sunk in the edges of said sign-board, as heretofore described with respect to the rod a.

For the purpose of preventing lateral oscillation of the sign-board when in its vertical position the legs b b' are provided, each of which is integral with one of the boards B B', respectively, and are of a length sufficient for the lower ends thereof to lie in the same plane with the lowermost point of said half-ball. Obviously said legs might be made separately, if preferred, from the boards, and the form of said legs may be varied for ornamental effect. Obviously, too, if said sign-boards are made of other material than wood—such, for instance, as sheet metal—the same will be secured to said bolts a and b² by means of clips fastened around said bolts and having their ends secured to the board. The same may be secured thereto by soldering, brazing, or like means. The groove a² is of sufficient depth and width that when the lower cut edges of the boards are driven therein the side walls of said grooves firmly clamp said boards and act to prevent the removal of the same therefrom.

The operation of my device is as follows: The device, provided with an appropriate sign upon the board, may be placed upon a sidewalk or another suitable place, preferably where there will be a slight draft of air. The action of the breeze will cause said sign to rock back and forth, thereby more quickly attracting the eye of the passer-by. Owing to the fact that the weight A is a half-ball the board may at times have a slight nodding movement laterally when inclined from its upright position. This slight eccentricity of movement, while not sufficient to permit the displacement of the sign from the position upon the walk, is a movement not possible with other signs of the class and unavoidably attracts attention. Obviously from the shape of the weight A the board may be placed in

any desired position and when released will return to its upright or vertical position. For the purpose of limiting said lateral movement somewhat the half-ball may be provided with a flattened or short cylindric central portion, as shown in Fig. 4. This operates to prevent lateral movement except under the effect of stronger drafts of air, with the result that such movements being other than the usual 10 and coming at uncertain intervals aid in attracting attention.

I claim as my invention—

1. A sign-board comprising a board of any desired material provided at its base with a 15 half-ball rigidly secured thereto and adapted to movably support the same and means acting to prevent lateral oscillation of the sign-board when in a vertical position.

2. A movable sign-board comprising a half-ball having a plane side provided with a groove extending diametrically across the same, a board of any desired material rigidly secured in said groove, means for permitting said sign to oscillate backwardly and forwardly and means acting to retain the same 25 from lateral oscillation when in its vertical position.

3. In a sign-board, the combination with a sign-board of a half-ball rigidly secured to 30 the lower margin of the same, and having the curved surface thereof adapted for contact with the ground, said sign-board being wider than the diameter of said ball and provided on one side thereof with a leg adapted for contact with the ground when the sign-board is in a vertical position.

4. In a sign-board, a half-ball having one plane surface and provided with a diametrical groove, a rod of metal rigidly secured in 40 said half-ball parallel with said groove and beneath the same, and having its ends projecting on either side of said half-ball, a plurality of boards having their end portions secured in said groove and projecting laterally 45 on each side of said half-ball, said laterally-projecting parts being secured to said rod ends, the upper ends of said boards being permanently secured together, and means acting to prevent the lateral oscillation of said 50 board when in its vertical position, comprising a leg on one side thereof extending downwardly in position to engage the ground.

5. In a sign-board, a half-ball having one plane surface and provided with a diametrical groove, a rod of metal rigidly secured in 55 said half-ball parallel with said groove and beneath the same the ends thereof projecting on each side of the half-ball, a plurality of boards having their end portions secured in said groove and projecting laterally on each 60 side of said half-ball said laterally-projecting parts being secured to said rod ends, the upper ends of said boards being permanently secured together and a leg on each side of said half-ball integral with said board and extending 65 downwardly to engage the ground when said board is in a vertical position.

6. In a sign-board, a half-ball having a plane surface and provided with a diametrical groove, a rod of metal rigidly secured in said half-ball 70 parallel with said groove and beneath the same, the end portion thereof projecting on each side of the half-ball, a plurality of boards having their end portions secured in said groove and projecting laterally on each side 75 of said half-ball, said laterally-projecting parts being secured to said rod ends, the upper ends of said boards being permanently secured together and a leg on each side of said half-ball integral with said board and extending 80 downwardly to engage the ground when said board is in a vertical position, said half-ball being provided with a relatively short central semicylindric portion adapted normally for contact with the ground. 85

7. An article of manufacture comprising a half-ball of metal or the like having a plane surface in the plane of a diameter, a groove extending diametrically across the same and a rod of metal rigidly secured in said half-ball 90 having its ends projecting outwardly therefrom, said rod being parallel with said groove and beneath the same and provided on one end with a head on the opposite end thereof with screw-threads adapted to receive a complementary nut. 95

In testimony whereof I have subscribed my name to this specification, in the presence of two subscribing witnesses, this 9th day of May, 1900.

CHARLES H. KEYSER.
